UNITED STATES PATENT OFFICE.

RANSOM SABIN, OF SHELBY, ASSIGNOR TO HIMSELF, AND ERWIN STANHOPE,
OF MEARS, MICHIGAN.

FOLDING BATH-TUB.

SPECIFICATION forming part of Letters Patent No. 400,119, dated March 26, 1889.

Application filed November 27, 1888. Serial No. 291,970. (No model.)

To all whom it may concern:

Be it known that I, RANSOM SABIN, of Shelby, in the county of Oceana and State of Michigan, have invented a new and Improved 5 Folding Bath-Tub, of which the following is a full, clear, and exact description.

The object of my invention is to secure a bath-tub which may be folded in small bulk when not in actual use and during transportation and storage, and the parts of which may be readily and conveniently brought into position for use, and after use folded again as readily and conveniently.

The invention will be first described, and 15 then specifically pointed out in the claim.

Reference is to be had to the accompanying drawings, forming a part of this specification, in which similar figures of reference indicate corresponding parts in all the views.

20 Figure 1 is an elevation of one of the sides of my bath-tub with the legs thereof in the folded position. Fig. 2 is a plan view of my bath-tub, showing the parts in the folded position. Fig. 3 is a side elevation thereof 25 with the parts in the position they occupy when the tub is ready for use. Fig. 4 is an end elevation taken when the parts occupy a position similar to the parts of Fig. 3; and Fig. 5 is a section taken on the plane of the 30 line xx , Fig. 3.

In the drawings, 1 1 represent the sides of the bath-tub, which are alike, and may be made of wood or metal, or wood or other material and metal combined. The ends of the 35 bath-tub are alike, and are composed of two parts, 2 2, of equal dimensions, hinged together at their inner edges by the hinges 3 3, and at their outer edges hinged to the sides 1 1 by hinges 4 4. These ends 2 2 I prefer to 40 make of thin sheet metal; but wood or other material may be used. A bolt, 15, is located on one of the parts 2 and a socket on the other part, so that they may be locked in the open position.

45 With each of the sides 2 2 I combine a pair of folding legs, 5 5. Each of the legs being constructed to operate in a similar manner, a description of one will suffice for all. Each leg is constructed to fold by securing it upon a pivot, 6, fixed upon the side,

and is secured in an opened or erect position by means of the pivoted catch 7, which the movement of the leg to its erect position throws out of its path, but which, after the leg has reached its socket in the stationary 55 piece 8, falls into a notch, 9, cut in the end of the leg, and locks it in the erect position. When it is desired to fold the legs again, the pivoted catch is removed from the notch on the leg and the leg rotated on its pivot to the 60 desired position.

To the side and end pieces I secure in any convenient manner a flexible sheet, 10, of some material impervious to water—as, for instance, rubber—of dimensions sufficient, 65 when in place, to provide ample space for the purposes of a bath. I also provide a strap, 11, for the purpose of dividing the flexible sheet 10 into two small compartments for the use of a child or young person. This strap 70 11 runs under the flexible sheet 10, and its ends may be brought up and united by a buckle, as shown in Fig. 2. It is obvious that when this strap 11 is drawn into nearly a horizontal position the flexible sheet will 75 be drawn up with it, as shown in dotted lines, Fig. 3, and thereby the compartments 12 13 will be formed. The strap 14 is similar in construction and operation to the strap 12, only located at the other end of the tub. 80

A head-strap may be provided extending from side to side, so that a bather may have a rest for the head while bathing.

The manner of operating my improved bath-tub will be obvious from the foregoing description of its parts.

This bath-tub will be found to be light in weight, portable, economical of house-space when desired, capable of reduction of bulk during transportation and storage, and economical in cost of construction.

Having thus fully described my invention, I claim as new and desire to secure by Letters Patent—

A folding bath-tub consisting in two parallel side bars, 1, having sockets 8 8 near their opposite ends, and latches 7 pivoted in front of the open sides of said sockets, the legs 5 5, pivoted between their ends to the side bars below the sockets, the upper ends 95 100

of the legs entering the sockets when swung into vertical position, and having notches to receive the latches 7, the end pieces, 2 2, hinged together at their adjacent ends, and 5 at their opposite ends hinged to the ends of the side bars to swing inwardly, the bolt 15, crossing the meeting ends of said end pieces, and the water-proof sheet 10, substantially as set forth.

RANSOM SABIN.
